UNITED STATES PATENT OFFICE.

WALTER C. GROSSE, OF CLEVELAND, OHIO, ASSIGNOR TO THE DRAPER MANUFACTURING COMPANY, OF CLEVELAND, OHIO, A CORPORATION OF OHIO.

CLOSURE MEANS FOR METALLIC CONTAINERS.

Application filed March 10, 1920. Serial No. 364,838.

This invention relates to containers, and refers more particularly to a means for closing the open end of metallic containers.

The principal object of said invention is to provide a removable closure for metallic containers adapted effectively to seal the same and prevent any leakage of contained liquids. To this end the closure means may be reinforced and the closure preferably is provided with a simple appliance for applying pressure thereto and for holding it securely in place.

A further object of this invention is to provide a device of the character specified, which will automatically accommodate itself to variations in the size, and to irregularities of the surface, of the open end of the container.

Another object of this invention is to provide in a metallic container, a closure, having associated therewith, a sealing means.

A still further object of this invention is to provide a closure for metallic containers, which is easy and inexpensive to manufacture, and strong and durable in use.

Other objects and advantages of this invention will appear in the course of the following description, and the particular features of novelty will be pointed out in the appended claims, it being understood, however, that various changes in the form and proportion of the device may be made without departing from the spirit of the claims.

In the drawings forming a part of this specification, and wherein like characters of reference denote similar parts in the several views:—

Figure 1, is a vertical section through the container, showing the closure therefor in position,

Fig. 2, is a top plan view of the container and closure,

Fig. 3, is an enlarged detail view, in section, of a portion of the container and closure,

Figs. 4 and 5 are sectional views of the gasket employed with the closure, and

Fig. 6, is an end view of one of the clamps used with the device.

Referring now, more particularly to the drawings, the numeral 5 denotes a container which is preferably formed of metal, and

which may be of any desired size and shape; said container being closed at one end, as shown at 6. The opposite end of the container is open and has the edge thereof overturned at 14, and terminates in an external depending flange 7 arranged parallel to and extending around the entire circumference of the container. 55

The open end of the container is partially closed by means of a head 8, having centrally thereof, a relatively large opening, and provided with a depending flange 9 adjacent said opening. As shown in Figure 3, this 65 head 8 is positioned within the container a short distance and is provided with an upstanding portion 10 which bears against the inner side of the body of the container.

The portion 10 is curled as shown at 11, 70 which curl terminates in a substantially U-shaped portion formed of flanges 12 and 13; the flange 13 fitting tightly between the body of the container and the above mentioned flange 7, and the curl 11 resting upon 75 the curl 14 thus seaming securely the head to the container, by a double locked seam.

Secured to the under side of the head 8 by means of bolts or other suitable securing means 15, is a spring collar formed of portions 16, 17 and flange 18. The section 16 is adjacent the head 8 and serves as a retaining means for the entire collar by means of the rivet 15 passing therethrough. The section 17 extends toward the opening in 85 head 8 and is angularly disposed with relation to section 16, and terminates in an upstanding flange 18 which bears against the depending flange 9, and tends to stiffen said flange 9 against the side of a plug which will be hereinafter described. The spring flange 90 is formed of a material which will be slightly resilient to obtain a spring pressed action on the flange 9, to secure a sealing relation for the stiffened flange at a distance below 95 the opening.

Removably positioned within, and closing the opening in head 8, is a plug, provided with a base 19 and an upstanding peripheral wall 20 at the edge thereof.

The wall 20 is provided with an external annular groove or depression 21, and its upper portion is bent at substantially right angles, forming a flange 22 which rests upon

the head 8 adjacent the opening therein, supporting the plug in position and limiting the downward movement of same when being placed in position.

- 5 Positioned within the depression 21 is an elastic or compressible gasket 23, formed of rubber or other like suitable material. The gasket 23, it is obvious, may be of any desired size and shape, conforming to the shape 10 or size of the interior of the depression 21. In Figures 4 and 5, there is illustrated the preferred and modified forms, respectively; the gasket of Figure 4, presenting in section, one curved side conforming to the shape of 15 the interior of the depression 21, and one flat side adapted to engage the flange 9, of head 8, while the gasket shown in Figure 5, is circular in cross-section.

When the gasket is in position in the depression 21, it extends a short distance beyond the plane of the side of the wall 20 of the plug, hence when the plug is in position within the opening in head 8, the gasket is under compression, providing a tight seal 25 with the flange 9.

With the construction of the gasket just described, and its association with the plug and the flange 9, it is obvious that various irregularities of manufacture which inevitably occur, will be overcome by the use of 30 said gasket, which automatically accommodates itself to such irregularities because of its compressible engagement with the flange 9.

35 It is further obvious that when the plug is inserted within the opening in head 8, the engagement of the gasket 23 with flange 9 will tend to force the flange 9 in a direction opposite to that which results by the pressure 40 of spring collar flange 18 on said flange 9; all of the elements co-operating to form a tight closure for the container.

Referring again to the above mentioned rivet 15, it is obvious that any number may 45 be provided for retaining the spring collar in position, but it has been found desirable to use only four, as illustrated in Figure 2. Secured to each rivet 15, is a clamp, 24, preferably narrow and elongated, and provided 50 with upstanding parallel lips 25, forming stiffening flanges and handles therefor.

To ensure easy operation of these clamps 24, each is secured by the rivet 15 at a point intermediate their ends, but preferably not 55 in the center thereof. Each clamp is further provided near one end, with an opening 26, the purpose of which will be hereinafter described.

From the construction of the clamps 24, 60 it can be seen that when the clamps are being turned to the position illustrated in full lines in Figure 2, there will be a certain movement of the above mentioned spring collar toward the opening in head 8, the 65 spring collar assuming a different position,

i. e. the position resulting from pressing against the flange 9, forcing said flange toward the opening in head 8. This is due to the slight elevation of the forward portion of the clamps 24 when they are resting on the 70 flange 22 of the plug. This is an additional advantage in obtaining a tight closure of the plug with the flange 9 of head 8.

The sealing of the container is effected by means of wires 27 connecting the clamps 75 24 when said clamps are in clamping position, which wires pass through the openings 26 therein and are sealed with the customary lead seals 28.

From the above description, it is believed 80 that the operation will be readily understood by those skilled in the art to which it appertains, so no further description is deemed necessary.

Having thus described my invention, what 85 I claim as new and desire to secure by Letters Patent of the United States, is:

1. A container comprising a main body portion provided with a head at each end, one of said heads having an opening therein, 90 a flange depending from said head adjacent said opening, a plug positioned within said opening, compressible means secured to said plug and pressing against said flange, means for clamping the plug within the opening, 95 and means secured to the head and to said clamping means and bearing against said flange whereby when said clamping means are in use, said flange will be forced in a direction opposite to that resulting from the 100 pressure of the above mentioned compressible means.

2. A closure for containers comprising, a head secured to said container and provided with an opening, a depending flange integral with said head and adjacent said opening, a spring collar secured to the under side of said head, a plug for said head provided with an external annular groove, compressible means secured within said annular 110 groove and bearing against the above mentioned flange, clamping means secured to the head and connected to said spring collar whereby said flange will be forced in a direction opposite to that resulting from the 115 pressure of the above mentioned compressible means.

3. In combination with a container, a head secured thereto and provided with an opening, a depending flange integral with said head and adjacent said opening, a spring collar secured to the under side of the head and engaging said flange, a plug removably positioned within said opening, a gasket secured to said plug exteriorly thereof and engaging said flange, clamping means for said plug secured to the head and connected to the spring collar, and means for sealing said plug within the opening.

4. Closure means for metallic containers,

- comprising a head for the container having a circular opening therein defined by an annular depending flange, an annular reinforcing collar for said flange engaging it 5 at a distance below the opening and braced diagonally against the head, a closure member for said opening, means associated therewith for securing compressible engage- ment between said member and flange to secure an augmented sealing relation at a distance below the opening, substantially as set forth.
- In testimony whereof I do now affix my signature.

WALTER C. GROSSER.
